United States Patent Office

Des. 185,405
Patented June 2, 1959

185,405

CALORIE COMPUTER

Thomas R. Welch, Los Angeles, and Martin S. Goldfarb,
Hollywood, Calif.

Application December 16, 1957, Serial No. 48,904

Term of patent 14 years

(Cl. D52—1)

FIG. 1

FIG. 2

FIG. 3

FIG. 4

FIG. 5

Figure 1 is a front view of a calorie computer, showing our new design;

Figure 2 is a rear view thereof;

Figure 3 is a view of the right side thereof;

Figure 4 is a front view showing the calorie computer of Figure 1 with its movable portions in a different position; and

Figure 5 is a rear view of the calorie computer of Figure 4.

The left side view of the calorie computer is similar to the right side view of Figure 3.

We claim:

The ornamental design for a calorie computer, substantially as shown and described.
